HEAT EXCHANGER

George A. Worn, Greenwich, Conn., and Edward A. Bertram, Mount Vernon, N. Y., assignors to The Lummus Company, New York, N. Y., a corporation of Delaware

Application August 1, 1942, Serial No. 453,234

6 Claims. (Cl. 257—234)

1

This invention relates to improvements in heat exchangers.

In connection with many chemical processes requiring heat for a reaction, it is common to employ heat exchangers to heat a stream of materials passing to a reaction chamber by heat exchange with a hot stream of reaction products discharged from the reaction chamber. In some processes, such as certain hydrocarbon conversion processes, for example, great heat and pressure are required in order to obtain a desired reaction. For example, in the chlorobenzene process for the manufacture of phenol, the conversion of chlorobenzene to phenol is carried out under a temperature exceeding 700° F. and a pressure exceeding 4,000 pounds per square inch. Since the heat exchanger is in communication with the reaction chamber or reaction coils, it is subjected to the strain of said enormous pressure. The usual type of heat exchanger is not capable of withstanding the strain of such conditions.

An important object of the present invention is to provide, for the aforesaid high pressure service, a relatively small unit heat exchanger designed throughout for adequate strength and durability, high heat transfer efficiency and low cost of manufacture.

Another object of the invention is to provide an improved heat exchanger tube unit of simple and compact construction and high heat transfer efficiency.

Another object of the invention is to provide a multi-unit high-pressure heat exchange apparatus, in which the units and their interconnections are designed to render the apparatus leak-proof throughout and, at the same time, enable ready disconnection, take-down and servicing of the units.

Other objects of the invention will appear hereinafter.

In the drawing:

Fig. 1 is a horizontal sectional view approximately on the line 1—1 of Fig. 5 and with parts broken away;

Fig. 2 is a vertical longitudinal sectional view of one of the improved heat exchanger units, approximately on the line 2—2 of Fig. 5 and upon an enlarged scale;

Fig. 3 is an enlarged vertical cross section on the line 3—3 of Fig. 2;

Fig. 4 is a perspective view of one of the improved tube units partly broken away; and

Fig. 5 is an end elevation of a plurality of the heat exchange units connected in series.

2

In accordance with a preferred form of embodiment of our invention, we have shown in Figs. 1 and 5 three of the improved heat exchanger units designated 10, 11 and 12 in a horizontal row and connected in series. It will be understood that such units may be so connected in any required number and that they may be arranged in superimposed banks if desired.

Each unit comprises an outer pipe or tube closed at one end, a cover detachably secured to the opposite end of said tube, and an inner tube unit connected to said cover. The outer tubes of the different units are, in the present instance connected in series for shell-side circulation of one fluid, and the inner tubing of the different units is connected in series for tube-side circulation of another fluid.

The outer tube of each unit is a welded construction formed for convenience in three sections. There is a long main tube section 13 which forms most of the length of the tube. A cover 14 is welded as at 15 to one end of said main section and forms a permanent closure therefor. An annular flange section 16 is welded as at 17 to the opposite end of section 13 and is formed with a thick peripheral flange 18, the tubular neck of which tapers so that its thickness decreases to the tube section 13. The bore of the head section is flared at its outer end as at 19, and the section is formed with a relieved face around the mouth of the bore and with a gasket-receiving groove 20 in said face. A thick cover plate or disk 21 has a similar face and a similar groove 22 in opposition to the face and groove respectively of the head section. A metal gasket ring 23 of a depth exceeding the combined depth of said grooves has its edges seated in the grooves. The grooves have flat bottoms and inwardly converging side walls, and the edges of the gasket are beveled in the grooves. Bolts 24 extend through holes in the flange 18 and the cover plate 21 and have nuts 25 screwed upon their opposite ends to secure the plate and hold the gasket under compression.

Cover plate 21 has a fluid inlet passage 26 and a fluid outlet passage 27 extending between its faces. Through most of the thickness of the plate said passages are parallel but, adjacent the inner face of the plate, they converge and open through flat abutments 28 at the bottom of flared counter-bores 29 at the inner face of the plate. Said abutments are disposed at right angles to the converging ends of the passages. The passages may be readily formed by boring inwardly part way through the cover plate and then bor-

ing from the inner face of the plate at an angle to meet the first bores. At the outer face of the plate the passages are counterbored to provide them with a flare or bevel seat 30.

Within the outer tube of each heat exchanger unit there is an inner tube unit forming a small tube bundle defined by a single bifurcated U-tube. Tubular stems 31 and 32, at the forward end of the outer tube, form the end portions of said U-tube. Stem 31 is the inlet stem and opens into a tubular fork 33. From said fork, parallel branch tubing 34 extends forwardly for the major portion of the length of the outer tube, forms return bends 35 and from said bends extends in a reverse direction to a tubular fork 36 opposite the first fork and connected to the outlet stem 32. In the present instance there are two of the branch tubes in each leg of the U-tube and they provide for divided flow from the stem 31 to the stem 32. In cross section the tubes are in a rectangular arrangement, as shown in Fig. 3. Their caliber is smaller than that of the stems. At their outer ends the stems 31 and 32 are secured in sealed communication with the passages 26 and 27 in the cover plate. The outer end portions of the stems diverge in order to reach the passages, and the ends of the stems contact squarely with the abutments 28 and are permanently secured to the cover plate at 28a by welding material in the counterbores 29. The tubes are thus integrated with the plate 21. For supporting the tubing centered within the bore of the outer tube the lower tube portions have supporting lugs 37 welded to them at points spaced therealong. Spacer blocks 38 disposed between and welded to the branch tubes at points spaced along the latter serve to hold said tubes in a transversely spaced relation.

The inner tube unit may be satisfactorily constructed in the following manner: Two pairs of tubes of a length suitable for forming the branch tubing are selected and adjacent end portions of the tubing in said pairs are forged together to form the return bends 35 between the pairs. The opposite end portions of the tubes in one pair are forged together to form the return bend or fork 33 and also form a nipple 33a. The opposite ends of the other pair of tubes are forged together to form the return bend or fork 36 and also form a nipple 36a. The said nipples are welded, as at 39, to short tube sections which form therewith the stems 31 and 32.

External tubing connects the inner tubing of the heat exchanger units for serial or parallel tube-side circulation through the units. There is a delivery tube 40 leading to the inlet passage 26 of the unit 10, a U-tube 41 leading from the outlet passage 27 of said unit to the inlet passage of unit 11, a U-tube 42 leading from the outlet passage of unit 11 to the inlet passage of unit 12, and a discharge pipe 43 leading from the outlet passage of unit 12.

Each of the said external tubes has a sealed connection with its respective communicating passage in the cover plate 21. For that purpose, each tube end communicating with a passage in one of the cover plates has an enlarged end 44 formed by upsetting the metal of the tube. Said enlarged end is seated in the flare 30 of the communicating passage and is preferably ground for line contact around the inside of the flare. There is a clamping device to maintain a compression seal of each of said tube ends. Each cover plate bears a pair of stud bolts 45 at opposite sides of each of its passages. A clamping yoke 46 has a

central bore receiving the unenlarged portion of the tube, and bores receiving the stud bolts 45. The outer ends of the latter bores are flared to receive conical washers 47, and nuts are screwed on the bolts against said washers. Between the inner side of the yoke and the enlarged tube end, a clamping ring 49 surrounds the tube. When the nuts are tightened, said ring is forced by the yoke against the rear shoulder of the enlarged tube end to force and hold the latter sealed against its seat.

Transverse piping connects the outer tubes of the exchanger units for flow of the fluid to be cooled through the units in series. The main tube section 13 of the unit 12 has welded thereto, adjacent one of its ends, a nipple 50 which communicates with an opening in said tube section and forms the inlet to the tube. Near its opposite end said tube section has an outlet opening communicating with a nipple 51 welded to the tube section and also welded as at 52 to a nipple 53. The latter is welded to the main tube section of unit 11 and opens through an inlet port near one end of that section. Near its opposite end said main tube section of unit 11 is in communication with an adjacent end portion of the main tube section of unit 10 through nipples 54 and 55 welded similarly to the nipples 51 and 53. A nipple 56 welded to the said tube section of unit 10, near the opposite end of the latter, forms an outlet for unit 10. The said nipples, individual to the respective units, may be welded in at the place of manufacture of the unit, and the appropriate nipples of the different units may be welded together at the place of erection of the apparatus.

Provision is made for protecting the inner tubing of each unit from erosion by the fluid entering the outer tube. For that purpose impingement shield plates 57 are welded to one side of the branch tubing 35 in a position to face the inlet port of the outer tube. The entire unit may also be provided with cradles 58 or similar devices to support the unit.

A highly efficient heat exchange unit is provided by this internal tube construction. It is possible by using the bifurcated tubes to obtain the largest amount of tube surface for the outer tube size and to still provide easy detachability of the entire unit. Leakage is prevented by integrating the tubes with the cover plates, it being understood that welding is preferred but that rolling or other sealing can be used. The external connections are also most effectively made by the particular means shown although it is possible to weld the external connections or to make other forms of joints if desired. The assembly is simple, easily and cheaply built and of particular advantage with high pressure requirements.

While we have disclosed a preferred form of embodiment of our invention, it will be understood that it is possible to modify details of the structure disclosed without departing from the invention as defined in the appended claims.

We claim:

1. In a heat exchanger comprising an outer tube having a fluid inlet and a fluid outlet and a closure for said tube detachably secured over one end thereof and having a fluid inlet passage and a fluid outlet passage, a bifurcated inner U-tube within said outer tube and comprising inlet and outlet stems forming the end portions of the U-tube and a plurality of tube branches leading from the inlet stem longitudinally within

the outer tube and forming return bends and thence leading back to the outlet stem for divided flow from the inlet stem to the outlet stem, said inlet and outlet stems being welded to said closure in sealed connection with said inlet and outlet passages respectively, projections borne by said inner tube to engage the interior of the outer tube and hold the inner tubing centered therein, spacing means secured to the branches of the inner tube to hold the branches in a spaced relation to each other, and impingement shield means borne by the inner tube and facing the said inlet of the outer tube.

2. In a heat exchanger of the double-tube type, comprising an outer tube adapted for passing a fluid longitudinally therethrough, a detachable closure for one end of said tube and having an inlet passage and an outlet passage, an elongated U-shaped inner tube within said outer tube and comprising an inlet stem and an outlet stem arranged alongside of each other in approximately the same plane and forming the end portions of the U-tube and both in permanent sealed connection with said closure at said inlet passage and said outlet passage respectively whereby said inner tube may be withdrawn from said outer tube upon disassembly of said exchanger, and a pair of tube branches, of approximately equal length and equal diameter leading forwardly from the inlet stem said branches being located in a plane at right angles to the plane of the stems and forming return bends in planes substantially parallel to said plane of the stems and thence leading rearwardly to the outlet stem and opening thereinto, such rearwardly leading branches being located in a plane at right angles to the plane of the stems, for evenly distributed forward and return passage of fluid from the inlet stem to the outlet stem, the forward and return reaches of said tube branches being, in cross section, all spaced in succession around a central space to form a tube bundle extending longitudinally within the outer tube and fully confined therein and of polygonal cross section, said bundle being supported centrally of the outer tube and being relatively closely surrounded by the latter and said stems, branches and return bends being continuous and integral and forming, together with said closure, a permanent unitary structure.

3. In a heat exchanger of the double-tube type, comprising an outer tube adapted for passing a fluid longitudinally therethrough and a detachable closure for one end of said tube and having an inlet passage and an outlet passage; an elongated U-shaped inner tube within said outer tube and comprising an inlet stem and an outlet stem arranged alongside of each other in approximately the same plane and forming the end portions of the U-tube and both in permanent sealed connection with said closure at said inlet passage and said outlet passage respectively whereby said inner tube may be withdrawn from said outer tube upon disassembly of said exchanger, a pair of superimposed tube branches, of approximately equal length and equal diameter leading forwardly from the inlet stem said branches being located in a common plane which is at right angles to the plane of the stems and forming superimposed return bends in planes substantially parallel to said plane of the stems and thence leading rearwardly to the outlet stem and opening thereinto, such rearwardly leading branches being arranged in superimposed relationship and being located in a plane at right

angles to the plane of the stems, for evenly distributed forward and return passage of fluid from the inlet stem to the outlet stem, the forward and return reaches of said tube branches being, in cross section, all spaced in succession around a central space to form a tube bundle extending longitudinally within the outer tube and fully confined therein and of polygonal cross section, said bundle being supported centrally of the outer tube and being relatively closely surrounded by the latter and said stems, branches and return bends being continuous and integral and forming, together with said closure, a permanent unitary structure.

15 4. A heat exchanger of the double-tube type and including an outer tube adapted for passing a fluid longitudinally therethrough, a detachable closure for one end of said tube and having an inlet passage and an outlet passage, an elongated U-shaped inner tube within said outer tube and comprising an inlet stem and an outlet stem arranged alongside of each other in approximately the same plane and forming the end portions of the U-tube and both in permanent sealed connection with said closure at said inlet passage and said outlet passage respectively whereby said inner tube may be withdrawn from said outer tube upon disassembly of said exchanger, a pair of parallel tube branches leading forwardly from the inlet stem and forming return bends in planes substantially parallel to each other and to said plane of the stems and thence leading rearwardly in parallel relationship, and opening into the outlet stem, for forward and return passage of fluid from the inlet stem to the outlet stem, the forward and return reaches of said tube branches being, in cross section, all spaced around a central space to form a tube bundle extending longitudinally within the outer tube and fully enclosed therein and of polygonal cross section, said bundle being supported centrally of the outer tube and being relatively closely surrounded by the latter and said stems, branches, and return bends being continuous and integral and forming, together with said closure, a permanent unitary structure.

5. In a heat exchanger including an outer tube with means for passing a fluid longitudinally therethrough, and inner tubing longitudinally arranged within the outer tube and comprising a plurality of sections of U-form with a common fluid inlet stem and a common fluid outlet stem both at one end of the tubing; a closure plate for the outer tube detachably secured and sealed to one end of the outer tube and having therethrough an inlet passage and an outlet passage both extending from the outer face of the closure plate to the inner face thereof and in sealed connection with said stems respectively whereby said inner tube may be withdrawn from said outer tube upon disassembly of said exchanger, said passages being flared outwardly at the outer face of the plate, a pair of outer pipes each having an enlarged end integral therewith, said pipe ends fitting in the flares of said plate passages respectively, clamping members for said pipe ends respectively, each of said clamping members having an opening receiving the unenlarged portion of its respective pipe and being formed to engage the shoulder formed by the enlarged end of the pipe, and screw means associated with each clamping member and connected to said closure plate at opposite sides of each of said passages to effect operation of either of said clamping members for clamping or release of either of said pipe

ends in the respective passage flare independently of the other pipe end.

6. In a heat exchanger comprising an outer tube having a fluid inlet and a fluid outlet and a closure for said tube detachably secured over one end thereof and having a fluid inlet passage and a fluid outlet passage, a bifurcated inner U-tube within said outer tube and comprising inlet and outlet stems forming the end portions of the U-tube and a plurality of tube branches leading from the inlet stem longitudinally within the outer tube and forming return bends and thence leading back to the outlet stem for divided flow from the inlet stem to the outlet stem, said inlet and outlet stems being secured to said closure in sealed connection with said inlet and outlet passages respectively, projections borne by said inner tube to engage the interior of the outer tube and hold the inner tubing centered therein, spacing means secured to the branches of the inner tube to hold the branches in a spaced relation to each other, and impingement shield means borne by the inner tube and facing the said inlet of the outer tube.
